DESIGN FOR A COMBINED CHAIR AND VIBRATOR

John Werner, Chicago, and Albert H. Zeigler,
Kenilworth, Ill., assignors to Aciform Corpora-
tion, Chicago, Ill., a corporation of Illinois

Application January 7, 1948, Serial No. 143,574

Term of patent 7 years

(Cl. D15—1)

To all whom it may concern:

Be it known that we, John Werner and Albert H. Zeigler, both citizens of the United States of America and residents of Chicago and Kenilworth, in the county of Cook and State of Illinois, respectively, have invented a new, original, and ornamental Design for a Combined Chair and Vibrator, of which the following is a specification, reference being had to the accompanying drawing, forming part thereof.

Figure 1 is a perspective view of a chair, showing our new design.

Fig. 2 is a top plan view thereof.

Fig. 3 is a side elevational view thereof.

Fig. 4 is a rear elevational view thereof.

We claim:

The ornamental design for a combined chair and vibrator, as shown.

JOHN WERNER.

ALBERT H. ZEIGLER.
